UNITED STATES PATENT OFFICE

150,637

DESIGN FOR A TOY BARROW

Pamelia F. Lewis, Sunland, Calif.

Application March 21, 1947, Serial No. 137,789

Term of patent 7 years

(CL. D34—15)

To all whom it may concern:

Be it known that I, Pamelia F. Lewis, a citizen of the United States, residing at Sunland, in the county of Los Angeles and State of California, have invented a new, original, and ornamental Design for a Toy Barrow, of which the following is a specification, reference being had to the accompanying drawings, forming a part thereof.

The side of the toy barrow, not shown in Figure 1, is substantially the same as the side shown in the latter figure.

The inner faces of the toy barrow sides are ornamented substantially the same as the outer faces.

I claim:

The ornamental design for a toy barrow, as shown and described.

PAMELIA F. LEWIS.
